UNITED STATES PATENT OFFICE.

FRANK M. PEARSON, OF MANCHESTER-IN-THE-MOUNTAINS, VERMONT.

DESIGN FOR A WATCH HOLDER.

Application filed October 9, 1923. Serial No. 7,435. Term of patent 14 years.

To all whom it may concern:

Be it known that I, FRANK M. PEARSON, a citizen of the United States, residing at Manchester-in-the-Mountains, county of Bennington, State of Vermont, have invented a new, original, and ornamental Design for Watch Holder, of which the following is a specification, reference being had to the accompanying drawing, forming a part thereof.

The figure is a view in elevation of a watch holder or support showing my new design.

I claim:

The ornamental design for a watch holder as shown.

FRANK M. PEARSON.
